POWDER DISPENSER

David A. Eolis, Mount Vernon, N. Y.

Application March 16, 1934, Serial No. 715,980

3 Claims. (Cl. 221—65)

This invention relates to powder dispensers used in connection with powder boxes and has for its object a means for controlling the cap of the said box and which means may be used 5 to screw on the cap or remove it. Another object of the invention is the duplicating of the invention and giving the various dispensers certain distinguishing features so that several people may use the powder but have different dispensers 10 from which to get the powder on their brushes.

These and other details and objects of the invention are more fully described in the following specification, set forth in the appended claims and illustrated in the accompanying drawing, 15 wherein:

Figure 1 shows a powder box with a dispenser attached to its removable cap.

Fig. 2 is a perspective view of a powder box with a plurality of dispensers attached to its 20 removable cap.

Fig. 3 is a side view of the dispensers in Fig. 2 and lined to represent different colors.

Fig. 4 is a similar view but showing a screw cap for each dispenser.

Fig. 5 shows a dispenser on a large cap to act as a base.

An objectionable feature in powder dispensers when associated with a powder box is that but a single person can satisfactorily use same but to 30 provide for several persons using the same box the present invention provides several dispensers to be mounted on the cap and given different distinguishing marks.

For the purpose of unscrewing the cap 10 of 35 the powder box 11 a trough-shaped dispenser 12 is rigidly secured to the cap and when the latter is removed a supply of powder may be put in the dispenser. To enable the user to take advantage of the cap and dispenser being removed 40 and not screwed on the box again, the cap 10,

as shown in Fig. 5, may be enlarged and made heavy enough to form a base to enable the dispenser to stand alone.

The duplicating of the dispenser, as shown in Figs. 2 and 3 necessitates them being set at an angle with the two dispensers 13 and 14 united by a strap 15 secured to the cap 16 and the same having their ends given distinguishing features as shown by the shading thereon.

Where it is desirable to leave one or the other 10 of the dispensers on the top of the box, the dispensers 17 and 18 in Fig. 4 may each have a cap 19 to be united and strengthened by the brace 20 and different colors may be applied to 15 the dispensers to distinguish them.

It is obvious that the parts of the invention may be otherwise arranged or modified without departing from the essential features above described nor from the scope of the appended 20 claims.

While a screw cap is shown in Figs. 3 and 4, any form of cap may be adopted, such as a frictional closure as shown in Figs. 1 and 2.

What I claim as new is:

1. In powder dispensers, the combination of a 25 powder box, a cap adapted to confine the contents of the box, a strip secured to the cap, and a trough secured to each end of the strip.

2. In powder dispensers, the combination of a 30 powder box having a nipple, a cap adapted to be fitted on the nipple, a flat arc-shaped strip secured on the cap, and arcuate troughs having closed ends and secured at the ends of said strip.

3. In powder dispensers, the combination of a 35 powder box having an opening and a nipple, a cap for the nipple, a flat strip on the top of the cap, and troughs possessing distinguishable features one from the other and secured at opposite ends of the strip.

DAVID A. EOLIS. 40
